STARTER JAW MESHING DEVICE

Richard E. Sears, Cleveland Heights, and Anthony F. Karlin, Bedford, Ohio, assignors to Jack & Heintz Precision Industries, Inc., Cleveland, Ohio, a corporation of Delaware

Application October 14, 1950, Serial No. 190,104

6 Claims. (Cl. 74—9)

1

This invention relates in general to engine starters and more particularly to improvements in means for meshing the starter jaw with the engine jaw.

One of the primary objects of the invention is to provide such a jaw meshing device that will insure a smooth positively locked engagement of the complementary jaws of the starter and the engine and avoid end abutment of the teeth of the jaws and resulting chattering without full drive engagement.

Another object is to provide such a device that will insure such proper mesh before full rotational power is applied by the starter motor to the starter jaw.

Another object is to provide such a device that utilizes the rotational drive of the motor shaft to extend the starter jaw into mesh with the engine jaw which includes a lost motion driving assembly whose rotation insures linear starter jaw extension into mesh with the engine jaw before coming into full driving relationship with the starter jaw.

A further object is to provide such a device with means for normally frictionally holding the starter jaw stationary but which automatically releases the friction lock on the starter jaw only upon full extension of the starter jaw into mesh with the engine jaw and upon the full drive engagement of the lost motion drive with the starter jaw.

With the foregoing and other objects in view, the invention resides in the combination of parts and in the details of construction hereinafter set forth in the following specification and appended claims, certain embodiments thereof being illustrated in the accompanying drawings, in which:

Figure 1 is a view, partly in side elevation and partly in longitudinal section of the starter, showing the starter jaw fully retracted and out of mesh with the engine jaw;

Figure 2 is a fragmentary view, partly in side elevation and partly in longitudinal section, showing the starter jaw extended short of full mesh with the engine jaw; the starter jaw being frictionally held against rotation by the ramped clamp ring assembly; the starter jaw cam being rotated by the driving barrel to linearly extend the starter jaw prior to rotational driving engagement of the barrel with the starter jaw.

Figure 3 is a similar view, showing the jaws fully meshed; the simultaneous driving engagement of the barrel with the starter jaw and its cam and the release of the friction clamp ring assembly from the starter jaw; and

Figure 4 is a view in perspective, partly broken

2

away, of the split friction clamp ring, its stationary holder and the pin between the clamp ring ends to prevent rotation of the ring.

Referring more particularly to the drawings, 5 the engine starter includes the usual casing 1 for housing an electric motor 2 having an output shaft 3 carried in bearings 4 and terminating in a sun gear 5. Sun gear 5 meshes with planetary gears, such as 6, which engage the usual friction plate torque release 7. The planetary gears 6 are 10 rotatably mounted on stub shafts 8 that are carried by the planetary gear carrier 9, which latter has a forwardly extending internally splined driving barrel 10.

15 In Figure 1, the starter jaw 11 is fully retracted within the starter and completely out of mesh with the engine jaw 12. Secured to the starter casing is a circular ring 13 having radially depending flanges 14. This ring 13 constitutes a 20 holder for a split metal clamping ring 15. A pin 16 extending through holder 13 also extends between the ends of the split clamp ring 15 to prevent rotation of ring 15 in stationary holder 13. The inner surface of clamp ring 15 is 25 inclined angularly radially inwardly, from right to left as viewed in Figures 1, 2 and 3 to form a ramp 17 and the outer surface of a portion of the head of the starter jaw 11 is similarly inclined to form a complementary ramp 18. When the 30 starter jaw is in fully retracted position, as shown in Figure 1, the starter jaw ramp 18 is riding inwardly on the full length of the clamp ring ramp 17 has compressed the spring clamp ring 15 so that the latter exerts a clamping action on the 35 starter jaw to prevent its rotation.

Now, as previously stated, the main objective is to insure full jaw mesh before full starter jaw drive. This is done without the necessity for solenoid actuated starter jaw extension devices.

40 The internal splines of the planet carrier barrel 10 mesh with relatively no lost motion with external splines 19 of a cam 20. The starter jaw has external splines 21, that are considerably smaller in width than cam splines 19, but which 45 splines 21 mesh, with lost motion, with the relatively wider internal splines of driving barrel 10. Cam 20 is free of attachment with starter jaw 11 but is spring urged into end engagement therewith. Cam 20 is provided with ramped 50 axially extending prongs 22 which bear against the pronged extensions of splines of the starter jaw.

When the electric motor is started, the drive of its shaft 3, through the planet system, regulated by the torque release, and through the driving

barrel 10 initially rotates cam 20. During this stage of operation, the barrel splines are engaged with the smaller starter jaw splines 21, and clamp 15 is frictionally clamping the starter jaw against rotation. The effect of the rotation of cam 20 is to have its ramped prongs 22 ride up on the pronged extensions of starter jaw splines 21 to force the starter jaw linearly outwardly, without rotation, toward and into partial mesh with engine jaw 12, as shown in Figure 2.

Further rotation of cam 20 by driving barrel 10 simultaneously brings about three results, namely full starter jaw extension into full mesh with the engine jaw; disengagement of clamp ring 15 from effective clamping action on the starter jaw; and full rotational driving mesh of the barrel internal splines with the smaller external splines of the starter jaw.

Thus the cam, and the lost motion drive between the barrel and the starter jaw, have served their useful purposes in linearly extending the starter jaw into mesh with the engine jaw prior to rotational drive of starter jaw by the driving barrel. Moreover, the friction clamp ring 15 has simultaneously served its useful purpose in clamping the starter jaw against rotation until this mesh has been accomplished by the starter jaw cam.

Thus, it will be seen that there has been provided a new and novel improved and foolproof starter jaw extension, meshing and driving means, which utilizes the motor shaft drive and which eliminates the necessity of complicated electrical time delay accessories, such as extra switches or solenoids, or the like.

We claim:

1. In combination in an engine starter, a casing, an electrical rotary driving motor, a starter jaw and an engine jaw, a barrel driven by said motor, said starter jaw being adapted to be driven, with lost motion, by said barrel, said starter jaw having a body with spaced inner end members extending into said barrel, a cam member mounted in said barrel coaxially with said starter jaw and adapted to be driven by said barrel without lost motion, said cam member having cam means adapted, upon rotation of said cam by said barrel, prior to the rotation by the latter of said starter jaw, to engage said jaw body end members to linearly extend said starter jaw into full mesh with said engine jaw prior to full rotative drive of said starter jaw by said barrel and means for clamping said starter jaw against rotation prior to full jaw mesh.

2. In combination in an engine starter, a casing, an electrical rotary driving motor, a starter jaw and an engine jaw, a barrel driven by said motor, said starter jaw being adapted to be driven, with lost motion, by said barrel, said starter jaw having a body with spaced inner end members extending into said barrel, a cam member mounted in said barrel coaxially with said starter jaw and adapted to be driven by said barrel without lost motion, said cam member having cam means adapted, upon rotation of said cam by said barrel, prior to the rotation by the latter of said starter jaw, to linearly extend said starter jaw into full mesh with said engine jaw prior to full rotative drive of said starter jaw by said barrel and friction means for frictionally clamping said starter jaw against rotation prior to full jaw mesh, said friction means being adapted to automatically release said friction clamp upon said starter jaw upon full mesh thereof with said engine jaw, said friction means comprising a sta-

tionary channeled ring carried by said casing, a split spring metal ring carried by said channeled ring and secured thereto against relative rotation, the inner surface of said split ring and the outer surface of the head of said starter jaw having complementary inclined ramps to compress said split ring into clamping relationship with said starter jaw when retracted and partially extended and to release said starter jaw from said friction clamping engagement after said starter jaw is fully extended into mesh with said engine jaw.

3. In combination in an engine starter, a casing, an electrical rotary driving motor, a starter jaw and an engine jaw, an internally splined barrel driven by said motor, said starter jaw having external splines to mate, with lost motion, with the splines of said barrel, a cam mounted in said barrel coaxially with said starter jaw and having external splines to mate directly with those of said barrel without lost motion, said cam member having cam means adapted, upon rotation of said cam by said barrel, prior to the rotation by the latter of said starter jaw, to linearly extend said starter jaw into full mesh with said engine jaw prior to full rotative drive of said starter jaw by said barrel and friction means for frictionally clamping said starter jaw against rotation prior to full jaw mesh, said friction means being adapted to automatically release said friction clamp upon said starter jaw upon full mesh thereof with said engine jaw, said friction means comprising a stationary channeled ring carried by said casing, a split spring metal ring carried by said channeled ring and secured thereto against relative rotation, the inner surface of said split ring and the outer surface of the head of said starter jaw having complementary inclined ramps to compress said split ring into clamping relationship with said starter jaw when retracted and partially extended and to release said starter jaw from said friction clamping engagement after said starter jaw is fully extended into mesh with said engine jaw.

4. In combination in an engine starter, a casing, an electrical rotary driving motor, a starter jaw and an engine jaw, an internally splined barrel driven by said motor, said starter jaw having external splines to mate, with lost motion, with the splines of said barrel, a cam mounted in said barrel coaxially with said starter jaw and having external splines to mate directly with those of said barrel without lost motion, said cam and starter jaw having loosely interlocking end prongs, inclined ramps on the side edges of said cam prongs adapted, upon rotation of said cam by said barrel, prior to the rotation by the latter of said starter jaw, to linearly extend said starter jaw into full mesh with said engine jaw prior to full rotative drive of said starter jaw by said barrel and means for clamping said starter jaw against rotation prior to full jaw mesh.

5. In combination in an engine starter, a casing, an electrical rotary driving motor, a starter jaw and an engine jaw, an internally splined barrel driven by said motor, said starter jaw having external splines to mate, with lost motion, with the splines of said barrel, a cam mounted in said barrel coaxially with said starter jaw and having external splines to mate directly with those of said barrel without lost motion, said cam and starter jaw having loosely interlocking end prongs, inclined ramps on the side edges of said cam prongs adapted, upon rotation of said cam by said barrel, prior to the rotation by the latter of said starter jaw, to linearly extend said

starter jaw into full mesh with said engine jaw prior to full rotative drive of said starter jaw by said barrel and friction means for frictionally clamping said starter jaw against rotation prior to full jaw mesh.

6. In combination in an engine starter, a casing, an electrical rotary driving motor, a starter jaw and an engine jaw, an internally splined barrel driven by said motor, said starter jaw having external splines to mate, with lost motion, with the splines of said barrel, a cam mounted in said barrel coaxially with said starter jaw and having external splines to mate directly with those of said barrel without lost motion, said cam and starter jaw having loosely interlocking end prongs, inclined ramps on the side edges of said cam prongs adapted, upon rotation of said cam by said barrel, prior to the rotation by the latter of said starter jaw, to linearly extend said starter jaw into full mesh with said engine jaw prior to full rotative drive of said starter jaw by said barrel and friction means for frictionally

10
